UNITED STATES PATENT OFFICE.

JOSEPH MALCOLM GREEN, OF COVINGTON, TENNESSEE.

DESIGN FOR A WATCH-FOB.

40,831.

Specification for Design. Patented Aug. 23, 1910.

Application filed June 16, 1910. Serial No. 567,336. Term of patent 7 years.

To all whom it may concern:

Be it known that I, JOSEPH MALCOLM GREEN, a citizen of the United States, residing at Covington, in the county of Tipton and State of Tennessee, have invented a new, original, and ornamental Design for Watch-Fobs, of which the following is a specification, reference being had to the accompanying drawing, forming a part thereof.

Figure 1 is a front view of a watch fob

showing my new design, and Fig. 2 is an edge view thereof.

I claim:

The ornamental design for a watch fob, as shown.

JOSEPH MALCOLM GREEN.
